UNITED STATES PATENT OFFICE.

ROLLO M. VICK, OF DETROIT, MICHIGAN, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,147,055.

Specification of Letters Patent. Patented July 20, 1915.

Application filed June 29, 1911. Serial No. 636,063.

To all whom it may concern:

Be it known that I, ROLLO M. VICK, a citizen of the United States, residing at Detroit, in the county of Wayne and State of Michigan, have invented certain new and useful Improvements in and relating to Filing Appliances, of which the following is a specification.

This invention relates to a filing appliance 10 or card index.

For the purpose of illustration, I have, in the accompanying drawings, shown and herein described one form of filing appliance embodying my invention.

15 Figure 1 is a longitudinal section through a drawer or holder showing a series of cards and a follower embodying my invention mounted therein. Fig. 2 is a perspective view of the follower. Fig. 3 is an inverted 20 perspective view of the follower. Fig. 4 is a longitudinal sectional view taken on a line passing through one of its supporting legs. Figs. 5 and 6 illustrate a slightly modified 25 form of the invention, Fig. 5 being a fragmentary longitudinal sectional view and Fig. 6 a fragmentary perspective of the drawer or holder.

In the drawings, 1 indicates a support or 30 holder. It preferably comprises a drawer having a bottom 1^a, sides 1^b (only one side being shown) a front wall 1^c and a rear wall 1^d. 1^e indicates a suitable handle carried by the front wall 1^c.

2 indicates the cards or papers which are 35 to be filed in the holder 1, one behind the other, and arranged on their lower edges, as is customary in keeping records of any kind by a card system. The cards 2 may include suitable index, division or title carrying 40 cards, such as may be found necessary in the system.

3 indicates a follower mounted in the holder. It is movable or adjustable from 45 end to end thereof in either direction to accommodate itself to the number of cards in the holder, or the increase or decrease in number thereof from time to time. The follower 3 comprises two members 3^a, 3^b, the member 3^a serving to carry a portion of the 50 cards and interposed between them and the bottom 1^a of the holder, and member 3^b operating as the back, abutment or rest for the rearmost card 2 and supporting it in an approximately vertical position. As is well 55 understood, by supporting the rear card in

this manner, all the cards in front of it are similarly supported. Preferably, the two members 3^a, 3^b, are formed integrally from a section of sheet metal which is bent along a transverse line 3^c to place said members 60 at the proper angles relative to each other.

3^d, 3^e, indicate a pair of legs or supports for the rear end of the member 3^a. These legs are preferably arranged near the opposite longitudinal sides of the follower. The 65 lower or free ends of the legs may be sharpened or pointed, as shown at 3^e, in order that, under the influence of the weight of the cards 2, they will slightly penetrate the surface of the bottom 1^a at all positions of adjustment. As a result of this operation, the follower will be prevented from slipping or moving in either direction, without first 70 slightly raising it or at least relieving it of the weight thereon, and will be held in any 75 place in which it is positioned.

As shown in the drawings, the card carrying member 3^a rests at its forward transverse edge upon the bottom 1^a, and is supported at its rear end by the legs 3^d. Since 80 the member 3^a is comparatively long, a considerable number of cards are carried thereby, the weight of which cards operate effectively to cause sufficient friction between the legs 3^d and bottom 1^a to prevent movement of the follower. 85

When the members 3^a, 3^b, are formed from sheet metal, I prefer to slit the metal on converging lines 3^f, and 3^g, and to bend the slitted portions backwardly slightly, as 90 shown, to form the legs 3^d. The upper transverse edge of the back 3^b is preferably turned over or doubled on itself, as shown at 3^h. This construction serves to strengthen the upper end of the back transversely and 95 also to form a smooth edge for the hands to engage with.

In Figs. 5 and 6 I have shown a slightly modified form of the invention. Referring to these figures 1 indicates the drawer or 100 holder having a bottom 1^a. 3 indicates the follower, which is mounted in the holder. 4 indicates friction increasing means mounted on or formed in the bottom 1^a and arranged in position to be engaged by the 105 ends of the legs 3^d. The friction increasing means preferably comprise a series of serrations or teeth 4^a which may be formed by cutting out short, transverse V-shaped grooves in the bottom 1^a. There is a series 110

of serrations for each leg 3^a and said series extends substantially from end to end of the drawer bottom. As will be apparent from the drawings, the legs 3^a are adapted to lie in alined grooves formed between two teeth 4^a in each series and will thus be held against forward or rearward sliding movement.

To those skilled in the art of making filing appliances of the class described, many alterations in construction and widely differing embodiments and applications of my invention will suggest themselves, without departing from the spirit and scope thereof. 15 My disclosures and the description herein are purely illustrative, and are not intended to be in any sense limiting.

What I claim is:—

1. The combination with a support, of a 20 follower arranged to rest on the support and adapted to support cards and similar articles thereon, and a leg carried by the follower and bearing on the support, the lower end of said leg being pointed and arranged to 25 penetrate the surface of the support to prevent movement thereon whenever the follower may be positioned.

2. The combination with a support or 30 holder, of a follower comprising a card carrying member having its forward or front edge adapted to rest on said support, a back fixed to said member for supporting cards in a substantially vertical position, and a leg for supporting the rear end of said card carrying member, the lower end of the leg being sharpened or pointed, whereby the 35 weight of the cards carried by the card carrying member causes the leg to penetrate the surface of the support to prevent movement of the follower.

3. The combination with a support, and a 40 series of cards mounted therein, of a follower for said cards comprising a card carrying member on which a portion of said cards are supported, a back for supporting the cards in substantially a vertical position, and a pair of legs for supporting the follower at one end, the legs terminating in 45 sharpened ends whereby they penetrate the surface of the support and prevent movement of the follower therealong.

4. A follower for a filing appliance formed 50 from sheet-metal, the metal being bent on a transverse line to form a card carrying member arranged to support a series of cards, and a back against which the rear card of the series rests, in combination with supporting devices having pointed ends arranged to penetrate the surface of a 55 support under the weight of the cards on the card-carrying member to prevent movement of the follower.

5. A follower for a filing appliance formed from sheet metal, the metal being bent on a transverse line to form a card carrying 60 member arranged to support a series of cards, and a back against which the rear card of the series rests, and the metal being slitted to provide a pair of legs which support the card-carrying member at one end, 65 the ends of the legs being pointed, whereby they penetrate the surface of a support and prevent movement of the follower.

6. The combination of a support provided 70 with a plurality of roughened surfaces extending longitudinally thereof, a follower movable on the support and comprising an angle plate, one member thereof serving to support a series of cards and the other member thereof operating as a back for the 75 cards, and spaced legs on which the card carrying member of the follower is supported arranged to aline with said roughened surfaces, the lower ends of said legs being pointed and engaging said roughened surfaces to 80 prevent movement of the follower along 85 said support.

7. The combination with a holder, of a 90 combined follower and support comprising a member on which cards or papers are supported and a back against which the rear-most card or paper rests, and friction increasing means between said combined follower and support and the bottom of the 95 holder, operating under the weight of the cards or papers to slightly penetrate the surface of the bottom and prevent movement of the said combined follower and support.

8. The combination with a holder, of a 100 device for supporting on their edges a series of cards or papers in said holder, said device having a member on which the rear-most cards or papers of the series are supported and supporting devices having their 105 lower ends pointed and arranged to penetrate the surface of the bottom of the holder to prevent movement of the card supporting device relative to the holder.

9. A follower formed from a section of 110 sheet metal and comprising a bottom member on which cards or papers are supported and a back for said cards extending upwardly from the rear edge of said bottom member, and a member for supporting said back, the said supporting member being 115 connected with said back and arranged to support the bottom at an angle when the follower is mounted on a support.

In testimony whereof I affix my signature, in the presence of two witnesses.

ROLLO M. VICK.
